(57) **CLAIM**

The ornamental design for a headset including a neckband, as shown and described.

DESCRIPTION

FIG. 1 is a perspective view of the headset including a neckband;

FIG. 2 is another perspective view of the headset including a neckband;

FIG. 3 is a top view of the headset including a neckband;

FIG. 4 is a bottom view of the headset including a neckband;

FIG. 5 is a right side view of the headset including a neckband;

FIG. 6 is a left side view of the headset including a neckband;

FIG. 7 is a front view of the headset including a neckband; and,

FIG. 8 is a rear view of the headset including a neckband.

1 Claim, 8 Drawing Sheets
